DOUBLE-TWIST TWISTING DEVICE

John Kermit Cochran, Conyngham, and Jacob Pfister, Hazleton, Pa., assignors to The Duplan Corporation, Hazleton, Pa., a corporation of Delaware

Application February 7, 1948, Serial No. 6,906

6 Claims. (Cl. 57—58)

1

This invention relates to apparatus for handling, treating, and translating filamentary material, such as yarn, and more particularly to apparatus for spinning or twisting yarn, such as double-twist spinning machine assemblies.

In certain double-twist yarn spinning machines known to the art, a hollow rotating spindle supports the yarn package or bobbin and rotates within a non-rotating yarn package carrier in association with a storage or takeup disc in such manner that two turns of twist are inserted in the yarn for each revolution of the spindle. In operation, these machines accomplish their purpose by leading the yarn or other filamentary material from the yarn package through a guide and over the top of the yarn package, thence down through the center of the yarn package, out of the spindle shaft and to a rotating storage disc below the package, thence up and outside the yarn package through a yarn guide, and finally to a takeup spool or package. These machines effectively impart the desired twist to the yarn, but under abnormal conditions, as when accidents occur, the machines are subject to damage which is extremely costly to property and dangerous to the operator or passersby.

In the normal operation of double-twist spinning machines, the yarn package is relatively stationary and does not rotate with the spindle which rotates inside the package carrier. It is common practice to provide a yarn package carrier or platform with ball bearings which engage the spinning spindle, and to prevent rotation of the platform or carrier by magnetism, gravity or other appropriate means to preclude undue rotation of the platform. A customary expedient to prevent the rotation of the package in normal operation is to tilt the spindle away from the vertical and to provide a weight in the base of the package platform, so that gravity tends to keep the package in the stationary or non-rotating position. In actual operation, however, it happens from time to time that the yarn package carrier accelerates and rotates with the spindle at a dangerously high speed. This occurs sometimes when the oil or grease in the ball bearings disappears or becomes fouled, or the parts become distorted, or for other reasons. As soon as the yarn package begins to rotate, and especially at high speeds, violent forces of unbalance are set into play and parts of the machine at times may be thrown away from and off the rapidly rotating assembly.

The present invention obviates the difficulties and disadvantages set forth above. This apparatus also avoids certain other prior difficulties which have been encountered when the filament strand or yarn was broken. Previously, when the strand or yarn was broken, the apparatus continued to operate and the yarn became snarled.

2

The present invention provides for automatic disengagement and stopping of the twisting spindle, as well as of the takeup spool, as soon as the yarn has become broken. The mechanism of the invention also operates when the tension of the yarn is reduced below the amount required to hold the mechanism in operating position. The invention also provides for intentionally breaking the yarn, thereby relieving the tension and stopping the machine when the yarn package rotates rapidly enough to set effective centrifugal forces into play.

The foregoing and further objects of the invention will be understood by reference to the drawing, in which

Figure 1 is a side elevational view of yarn twisting and translating apparatus;

Figure 2 is a top view of the movable yarn guide and associated locking element;

Figure 3 is a plan view of the tip of the yarn package carrier shaft with an intercepting element in operating position and with the flyer removed;

Figure 4 is a cross-section of the top portion of the yarn package carrier shaft and associated parts in the non-intercepting or normal position; and

Figure 5 is a cross-section on line 5—5 of Figure 3 similar to Figure 4, with the intercepting element in operative position.

Although it is to be understood that this invention relates to and is applicable to various types of yarn treating and translating apparatus, a particular embodiment thereof is shown with respect to a double-twist spinning machine. Referring to Figure 1, a spinning spindle assembly 1, known in the art, comprises a spring-held bolster 2 in which is rotatably mounted a spindle, as is known in the art, on which is fitted a whorl 3 and a yarn storage or takeup disc 4, both of which are driven by suitable driving means such as a belt 5. The upper portion of the spindle assembly 1 supports a yarn package platform 6 (indicated by dotted lines) which normally does not rotate with the shaft of the spindle assembly 1 because of a weight 7 and bearings secured therein. The weight, by force of gravity when the spindle is in tilted position, prevents rotation of the package platform and confines the movement thereof to a restricted degree of oscillation. A package 8 of yarn 9 rests on the platform 6, and is surmounted by a collar 11 supporting a flyer 12 which conveniently may be light strips of stiff wire looped at the ends thereof. The flyer, as is well known, may be surrounded by a ring or "cage" to prevent tangling of the yarn when the apparatus is started. The normally fixed package platform 6 also supports an intercepting element 13, which, as shown in Figure 1, comprises an upstanding coil spring surmounted by and sup-

porting a weight 46. The interceptor 48 may, of course, be of any convenient construction, which, upon accidental undue rotation of the platform 6, will be centrifugally ejected or flung outwardly by virtue of the weighted portion 46 being impelled away from close proximity to the yarn package 8 and across the yarn path of travel.

In normal operation, the whorl 3 is in driving engagement with the belt 5, causing a shaft within the spindle 1 to rotate together with the storage disc 4, in known manner. A strand of the yarn is taken off the yarn package 8 and fed through the eye or loop at the end of the flyer 12, and into the tip 15 of a hollow shaft which supports the package on the package platform. The end of the yarn then internally traverses the entire length of the bobbin or package through the center of the shaft thereof and is led out, in normal manner understood by those skilled in the art, on to the storage disc 4. When the machine is operating at normal speeds, the yarn 9 forms a "balloon" between the storage disc 4 and yarn guide 17, the yarn at one point in the "balloon" being shown at 16, and is led through a fixed yarn guide 17, and thence through a movable yarn guide 18. From the yarn guide 18, the strand 9 is guided at 19, for example, by a loop of wire, on to a takeup spool or bobbin 21 and there collected. The spool or bobbin 21 is conveniently supported by angle arm 22. In this type of double-twist apparatus, the initial twist is inserted in the yarn between the supply package and the storage disc 4, due to the rotation of the spindle blade, and additional twist is inserted by the rotation between the storage disc 4 and the guide 17. The twisted yarn collected on the takeup spool or bobbin 21 is then ready for further processing or for delivery to the customer upon dismounting the spool or bobbin from its support.

In the particular embodiment of the apparatus as shown in Figure 1, an upright frame member 31 carries a rigid slide 32, which may be suitably braced as at 33. A movable or slideable base 34 supports the spindle assembly 1 which extends through an opening in the top of the base to accommodate the bolster 2. The slide 32 is provided with an elongated slot (not shown) through which the spindle bolster extends and which permits longitudinal movement of the spindle assembly together with the base 34 along the slide but without disengagement therefrom. The base 34 comprises, as is known in the art, a flat top surface 35 and two side portions 36 integral therewith and adapted to track along the side faces of the slide 32. In order to prevent the base 34 from upwardly disengaging the slide 32, the lower edge of the side panels 36 are preferably understruck so that at least a portion of the interior of each of the four sides of the base 34 is in sliding engagement with each of the four exterior sides of the slide 32.

The upper end of the base 34 is provided with a welded or upstruck lug 37 to which is attached, through a hole therein, or by other suitable means, one end of a spring 38 which is anchored at its opposite end to an arm 36 keyed to a shaft 41. Other resilient means, obviously, may be used in lieu of the spring 38 to hold the base in operating position so that the whorl 3 is held in driven contact engagement with the belt 5. The shaft 41 is journaled near one end in a bracket 42 and near the other end in the fixed slide 32. At the top of the shaft 41 a handle 43 is keyed to permit manual rotation of the shaft, and adjacent thereto, also keyed to the shaft, is a locking disc 44

having a locking notch 45 in the periphery thereof.

The bracket 42 also supports a cross bracket 46 which is riveted thereto. The cross bracket 46 has an arm 47 which supports the wire yarn guide 17 by any suitable means, such as by a screw or bolt, and also carries a pivot shaft 48. A movable yarn guide support 49 rocks on the shaft 48 (see Figures 1 and 2) and is bifurcated to accommodate a pin 51 carrying the movable yarn guide 18. A spring 52 is connected between a point 53 on the guide support 49 and a point 54 on the cross bracket 46. The action of the spring 52 tends to impel the yarn guide 18 upwardly against the tension of the yarn 9 when the machine is in operation; and when the yarn 9 is broken or disengaged from the yarn guide 18, the guide support 49 is moved upwardly by the spring 52.

The opposite key end 50 of the guide support 49 normally engages the notch 45 in the locking disc 44. When the yarn guide 18 is in the inoperative position, as shown by the dotted lines in Figure 1, the movement thereof disengages the opposite key end 50 of the support 49 from the locking disc 44 and permits the spring 38 to rotate the shaft 41 and hence arm 39 to a lower position, thereby lowering the base 34 along the slide 32. The sliding movement of the base 34 is caused by gravity after release of the tension of the spring 38, and also by oscillation of the resiliently-mounted spindle assembly.

It is obvious that the details of construction of the movable yarn guide 18 and the supports therefor may be varied as desired. For example, as shown in Fig. 6, the fixed yarn guide 17' may be mounted independently of the supports for the movable yarn guide, and instead of utilizing the spring 52, the pivot shaft 48' may be positioned close to the guide 18' and distant from the key 50' so that the normal tension of the yarn 9' operates against gravity. With this arrangement, when the yarn is broken or otherwise disengaged, the force of gravity will operate against the lever arm 48' to withdraw the key portion 50' therefrom from the notch 45'.

As the base 34 travels along the slide 32, which is what happens when the apparatus is in the inoperative position, as when the yarn 9 is broken, the whorl 3 is disengaged from the driving element 5. A fixed bumper or brake 61 is positioned in the path of longitudinal travel of the whorl 3 and operates frictionally to stop the spinning whorl upon release of the base 34 from the normal operating position.

The takeup spool 21 may be arranged in any convenient manner, but it is preferred to provide a frame 63 supporting a driving roll or wheel 64 driven by any suitable means (not shown) in normal engagement with the spool, or with the spool shaft. When the yarn breaks, it is also desirable to disengage the takeup spool from its driving element 64. This is accomplished by providing a disengaging arm 65 rigidly secured to the base 34, and hence slideable therewith. The frame 63 conveniently supports the fixed yarn guide 19 and also pivotally (at 66) carries the angle arm 22 supporting the spool 21. The opposite end 67 of the arm 22 is arranged in line with the disengaging arm 65, so that when the base 34 shifts to the inoperative position, the arm 65 travels diagonally downwardly to abut the arm end 67 and thereby to disengage the reel 21 from the drive wheel 64, as shown in dotted position in Figure 1.

The intercepting element or yarn interceptor 13, as shown in Figure 1 in solid lines, is normally out of the path of travel of the balloon of yarn 16. However, when the platform 6 begins to rotate, the interceptor 13, which is preferably weighted at the end, is thrown into the yarn path 16 and breaks the yarn to relieve the tension at the yarn guide 18, and hence to stop the motion. The interceptor may be otherwise constructed as shown in Fig. 7, by providing a sharp-edged strip 13' of spring metal, such as spring steel, supporting the weight 14', so that in the operating or intercepting position a cutting action is applied to the yarn balloon 16'. The interceptor 13 effectively and rapidly stops the machine whenever the yarn package begins to rotate at sufficient speed to throw the interceptor into the path of the yarn. In the event of a condition arising which initiates rotation of the yarn package 8, the interceptor 13 on platform 6 tends to travel at increasingly higher speeds. At these intermediate speeds, the interceptor is travelling at a slower rate of rotation than the takeup disc 4, and therefore traverses, and hence cuts or breaks, the yarn in its path.

It is obvious that other stopping arrangements for the apparatus may be employed, and that so long as it is the breakage of the yarn which sets the stop motion in operation, the interceptor 13 will function according to the invention.

An alternative centrifugal intercepting element is shown in Figures 3, 4, and 5. The top of the yarn package or bobbin supporting shaft 71 (which is, in turn, a part of, or supported by, the platform 6 of Figure 1) is provided with a hollow projection 72 having a transverse acentric slot 73 and an intercepting pin 74 slidable in and out of the slot. The slot is long enough to accommodate a substantial portion of the length of the pin, as shown in Figure 4; and, as shown in Figure 5, the pin 74 is sufficiently long to engage the flier 75 when in the operative position. If desired, the pin may project slightly from the slot when in the retracted position. The flier 75 is supported by a collar 76 which fits over the projection 72. In normal operation, the package carrier does not rotate, and the flier is rotated relatively slowly by the yarn coming off the supply package, but when the package carrier begins to rotate, the pin 74 is centrifugally impelled out of the slot 73 and engages the flier 75. The flier, as in the flier 12 shown in Figure 1, is provided at its end with a yarn guiding loop or pigtail (not shown), and when its normal rotation in relation to the yarn package is impeded, breakage of the yarn results and sets the stop motion apparatus into operation, as described, or in other manner as understood in the art.

In view of the many changes and modifications that may be made without departing from the principles underlying the invention, reference should be made to the appended claims for an understanding of the scope of the protection afforded the invention.

What is claimed is:

1. A yarn spinning apparatus comprising a driven spindle assembly including a storage disc, a yarn guide between which and said disc the yarn describes a yarn path, a normally stationary yarn package carrier supported by said spindle assembly and an interceptor supported by said carrier, said interceptor being normally positioned out of the yarn path and when said platform is ro-

5 tated said interceptor being impelled by centrifugal force across the yarn path.

2. A yarn spinning apparatus comprising a rotatable spindle assembly including a storage disc, a bobbin holder mounted on said spindle and normally non-rotating, a yarn bobbin on said holder, a yarn guide between which and said disc the yarn describes a yarn path, an interceptor supported by said bobbin holder and normally out of engagement with the yarn path, a movable yarn guide and a stop motion device normally locked out of operative position by said yarn guide in its operative position, said interceptor upon rotation of the bobbin holder being adapted to be impelled by centrifugal force across said yarn path to relieve the yarn tension on the yarn guide.

20 3. A yarn twisting apparatus comprising a downwardly movable base, a twisting spindle supported by said base, a normally non-rotating yarn package platform supported by said spindle, and a movable yarn guide, said guide being held in operating position by yarn tension and locking said base in operating position, said guide in the inoperative position releasing said base from operating position and permitting release motion of said base by gravity.

25 4. A yarn spinning apparatus comprising a movable support, a downwardly sloping slide for said support, a spindle mounted on said support, a bobbin holder mounted on said spindle, said holder being rotatable but non-rotating in the operative position, a driving element for said spindle, a movable yarn guide held in the operative position by yarn tension and holding said support in such position that the spindle is in engagement with said driving element, said guide when in the inoperative position releasing said support for motion by gravity along said slide.

30 5. A twisting device for yarn comprising a movable base, a twisting spindle mounted thereon, a driving member normally in contact with said spindle, a movable yarn guide, and a normally stationary bobbin platform supported by said spindle, said guide being retained in the operating position by yarn tension and holding said spindle in contact with the driving member, said guide in the inoperative position releasing said base to separate the spindle from the driving element.

35 6. A twisting device for yarn comprising a movable base, a twisting spindle and a spool drive-disengaging element mounted thereon, a spindle driving member normally in contact with said spindle, a movable yarn guide, a normally stationary bobbin platform supported by said spindle, a driven takeup spool, and a spool drive normally in contact therewith, said guide being retained in the operative position by yarn tension and holding said spindle in contact with the driving member, said guide in the inoperative position releasing said base to disengage said driving members respectively from the spindle and from the reel.
